UNITED STATES PATENT OFFICE.

LORNE A. GRIFFIN, OF EVANSTON, ILLINOIS, ASSIGNOR TO AMERICAN STEAM CONVEYOR CORPORATION, OF CHICAGO, ILLINOIS, A CORPORATION OF NEW YORK.

ASH-CONVEYER ELBOW.

1,258,893.

Specification of Letters Patent.

Patented Mar. 12, 1918.

Application filed November 9, 1917. Serial No. 201,166.

To all whom it may concern:

Be it known that I, LORNE A. GRIFFIN, a citizen of the United States, residing at Evanston, in the county of Cook and State 5 of Illinois, have invented a certain new and useful Improvement in Ash-Conveyer Elbows, of which the following is a full, clear, concise, and exact description, reference being had to the accompanying drawings, 10 forming a part of this specification.

My invention relates to ash conveyer systems, and more specifically to an improved elbow forming part of an ash conveyer conduit, and has for its general object the provision of a practical and efficient elbow 15 whose arms form an obtuse angle or an angle other than ninety degrees.

It is the primary object of the invention to provide an elbow of the class described, 20 in which the wear of the parts is reduced to a minimum, and in accomplishing this object I provide the novel arrangement pointed out in the following description, in which reference is made to the accompanying 25 drawings, wherein—

Figure 1 is a vertical cross sectional view of the elbow of my invention, showing parts of the ash conveyer conduits attached thereto; and

Fig. 2 is a vertical cross sectional view taken along the line 2-2 of Fig. 1, looking in the direction indicated by the arrows.

Similar characters of reference refer to similar parts in both views.

The improved elbow of my invention comprises a casing 3 having the substantially cylindrical portions 4 and 5 which together form an obtuse angle. The upper end 6 of the elbow is provided with the straight walls shown at 7 and 8 in Fig. 2. Between the straight walls 7 and 8 and the cylindrical elbow, I provide the shoulders shown at 9 and 10 in Fig. 1. The upper side of the elbow between the flange 11 and the end wall 12 is provided with an opening 13 arranged to be closed by the cover plate 14 held in place by the screws 15-15. The shoulders 10 provided on the cylindrical portion 4 of the elbow are arranged to support the liners shown at 16 and 17. These liners, as most clearly shown in Fig. 1, are arranged parallel to the axis of the cylindrical portion 4 of the elbow. The shoulders 9 serve to support the liner 18, which lies in a plane normal to the axis of the cy-

lindrical portion 5 of the elbow; or, in other words, lies at right angles to the conveyer conduit 19, which is attached to the cylindrical portion 5. The flange 11 of the cylindrical portion 4 is connected with the conveyer conduit shown at 20, which extends outwardly and communicates with an ash tank. If desired, the cylindrical portion 4 may be provided with a throat liner 21. In removing the liners, the cover plate 14 is removed and the liner 18 pulled upwardly out of the elbow. The liner 16 may then be removed and the liner 17 moved downwardly out of the flange 11, whereupon its removal is permitted.

The operation of the device is as follows: The ashes are projected through the pipe 19 in the direction indicated by the arrow, and are caused to impinge against the liner 18. After striking this liner they are caused to 75 pass outwardly through the cylindrical portion 4 of the elbow, and through the conduit 20 into the ash tank, from which the ashes may be removed into a vehicle. It will be observed that the wear on the liner 18 is 80 reduced to a minimum due to the fact that it assumes a position at right angles to the flow of the ashes. If the liner 18 were held in position substantially parallel with the liners 16 and 17, the ashes would strike the 85 liner at an angle and wear out the liner very rapidly, due to the wiping and cutting action of the ashes. Because of the location of the liner 18, as shown in Fig. 1, the ashes are caused to strike directly, without any 90 cutting action, and after striking the liner, they are caused by the steam which is utilized in the conveyer system to pass outwardly through the conveyer 20.

Although I have shown and described the 95 liners 16, 17 and 21 as being provided in the section 4 of the elbow, I desire to have it understood that these need not necessarily be employed, since the wear in this section of the elbow is almost negligible.

Having thus described my invention, what I claim as new and desire to secure by Letters Patent of the United States is:

1. An elbow comprising an intake conduit and an outlet conduit arranged at an angle 105 to said intake conduit, the inner side of said intake conduit and the adjacent side of said outlet conduit being open and having the walls thereof extended to form side members provided with shoulders, wear liners 110

supported by said shoulders at right angles to said intake conduit, and closing the open side of said outlet conduit respectively, the said last-named liners being held in place by 5 said first-named liner, and means for holding said first-named liner in place.

2. An elbow comprising an intake conduit and an outlet conduit arranged at an angle to said intake conduit, the inner side of 10 said intake conduit and the adjacent side of said outlet conduit being open, wear liners supported at right angles to said intake conduit and closing the open side of said outlet respectively, the said last-named 15 liners being held in place by said first-named liner, and means for holding said first-named liner in place.

3. An elbow comprising an intake conduit and an outlet conduit arranged at an angle 20 to said intake conduit, the inner side of said intake conduit and the adjacent side

of said outlet conduit being open, wear liners supported at right angles to said intake conduit and closing the open side of 25 said outlet respectively, the said last-named liners being held in place by said first-named liner.

4. An elbow comprising inlet and outlet conduits joined at an angle, a removable wear liner forming the outer side of said outlet conduit, a wear liner extending at an angle to said first-named wear liner, and closing the adjacent end of the intake conduit and extending at right angles thereto, and a third liner held in place by said first-named wear liner.

In witness whereof, I hereunto subscribe my name this 5th day of November, 1917.

LORNE A. GRIFFIN.
